DESIGN FOR A COMBINED ASH TRAY AND MATCH BOX HOLDER

Sally Oestreicher, Akron, Ohio

Application March 11, 1943, Serial No. 109,723

Term of patent 7 years

To all whom it may concern:

Be it known that I, Sally Oestreicher, a citizen of no country, residing at Akron, in the county of Summit and State of Ohio, have invented a new, original, and ornamental Design for a Combined Ash Tray and Match Box Holder, of which the following is a specification, reference being had to the accompanying drawing, forming part thereof.

I claim:

The ornamental design for a combined ash tray and match box holder, as shown.

SALLY OESTREICHER.
